UNITED STATES PATENT OFFICE.

EDWARD W. ISOM, OF LOCUST VALLEY, NEW YORK, ASSIGNOR TO SINCLAIR REFINING COMPANY, OF CHICAGO, ILLINOIS, A CORPORATION OF MAINE.

ART OF CRACKING HYDROCARBONS.

Original application filed November 4, 1918, Serial No. 261,109. Divided and this application filed October 4, 1924. Serial No. 741,580.

To all whom it may concern:

Be it known that I, EDWARD W. ISOM, a citizen of the United States, residing at Locust Valley, in the county of Nassau, State of New York, have invented certain new and useful Improvements in the Art of Cracking Hydrocarbons; and I do hereby declare the following to be a full, clear, and exact description of the invention, such as will enable others skilled in the art to which it appertains to make and use the same.

This invention relates to improvements in processes of cracking heavier hydrocarbon oils, such as heavier petroleum oils and distillates, for the production of lighter hydrocarbon oils therefrom by distillation under pressure. More particularly, the present invention relates to improvements in the operation of circulatory pressure stills in which circulation is effected by mechanical forcing means such as a pump.

In cracking petroleum oils and distillates by distillation under pressure, temperatures between about 600° and 900° F. and pressures of as much as 100 pounds per square inch or more are commonly employed. For the most efficient operation of circulatory pressure stills, it is necessary that the oil be quite rapidly circulated and preferably some mechanical forcing means, such as a pump, is employed to effect rapid circulation. The use of a mechanical circulating means under these conditions, however, involves special difficulties.

As the temperature of the hot circulating oil is far above its ignition temperature if exposed to the atmosphere and since the oil is under a high pressure, one of the problems encountered is the prevention of leakage of the hot inflammable oil. This problem is accentuated by the wide range of temperatures to which the mechanical elements of the pump are subjected. It is also desirable to protect the mechanical elements of the pump from the hot oil at cracking temperature to as great an extent as possible. These and other factors which influence the continuity of operation of the pump are particularly important with respect to circulating pumps employed in circulatory cracking systems since uninterrupted operation of the pump is necessary to protect the heating sur-

faces of the pressure still during the cracking operation.

It is one of the objects of the present invention to provide an improved process of distilling oils under pressure in which mechanical circulation is employed and in which the mechanical circulating means are operated in an improved manner whereby difficulties such as those referred to above are avoided or minimized. Other and further objects will appear as the description proceeds.

According to the present invention, a stuffing box is provided about the shaft or other extension operating the mechanical forcing elements within the pressure still and relatively cold oil is circulated through a housing arranged externally of the stuffing box under a pressure somewhat in excess of the pressure prevailing in the still. Escape of the hot oil at cracking temperature is thereby avoided since any leakage past the stuffing box will be of cold oil into the still rather than of hot oil out. The mechanical elements of the circulating means are also cooled and protected thereby.

The amount of cold oil employed may be just sufficient to prevent the escape of the hot circulating oil, or an additional amount of cold oil may be employed to secure an increased cooling effect. After circulation about the stuffing box, the cold oil may be introduced into the pressure still, or it may be cooled and recirculated. Fresh oil to maintain the still charge may be employed in this manner, and may be withdrawn from a supply and introduced wholly into the still after being used to cool and protect the mechanical circulating means, or an additional amount of fresh oil may be employed to obtain an increased cooling effect and the excess returned to the common supply where it is cooled by intermixture with the remaining fresh oil.

In the accompanying drawings I have disclosed one form of apparatus adapted for practicing the process of the present invention. It is to be understood, however, that this disclosure is for the purpose of assisting in the comprehension of the invention, which may be practised in a great variety of apparatus. The following more

detailed description and illustration of one form of the process of the invention is for the purpose of exemplification only, and the scope of the invention is defined in the following claims in which I have endeavored to distinguish it from the prior art so far as known to me without, however, relinquishing or abandoning any portion or feature thereof:

10 In the drawings accompanying and forming a part of this application:

Fig. 1 is an enlarged view of a circulating pump adapted for practicing the process of the invention with parts broken away,

15 Fig. 2 is an end elevation of a still embodying a pump of the type illustrated in Fig. 1, and

Fig. 3 is a side-elevation partly in section of the still illustrated in Fig. 2.

20 The still illustrated in the drawings is of the type described and illustrated in Patent No. 1285200 granted to the Sinclair Refining Company November 19, 1918, on my application.

25 In the operation of the apparatus illustrated, the heavy oil to be cracked is circulated through a battery of heating tubes located in the furnace A from the tank C by a forcing device B and thence back to the tank C. The vapors collecting in the upper part of the tank C may be withdrawn and condensed in a condenser 59, diagrammatically illustrated in Fig. 2, and the pressure in the still may be controlled by regulating the valve 60 located in the outlet of the condenser. The oil is maintained at the appropriate level in the tank C by replenishing or replacing the oil driven off in the distillation with fresh oil as the distillation 30 proceeds.

40 In the apparatus illustrated, the furnace comprises horizontal flues 6 and 7, communicating with fire boxes arranged upon opposite sides of the flues, and connecting through outlet flues 10 and down-comer flues 12 to outlet flues 13, leading to suitable stacks. The furnace structure may be refractory brick or the like resting upon a suitable foundation 14 and re-enforced by 45 buckstaves 15 connected by tie bars 16. The arches 17 and 18 and the floors 19 and 20 of the heating flues are perforated vertically at suitable intervals for the passage of batteries of heating tubes or pipes 22 which 50 extend vertically through the flues and are connected at top and bottom respectively to the manifolds or headers 23 and 24. The upper manifold comprises an intermediate main supply pipe 25 arranged above the 55 roof of the flues and intermediate the latter, the main pipe being provided with parallel laterals 26 connected to the main pipe by branches 27. Each of the laterals 26 is formed with a series of upwardly and 60 downwardly projecting connection branches 65

28 and 29, there being an upper branch in registry with each lower branch. The lower manifold 24, except in the respect herein-after indicated, is similar to the upper manifold 23, and the heating tubes 22 extend vertically between the respective branches on the laterals of the upper and lower manifolds and through the roof and floor of the respective flues. The upper branches 28 of the upper manifold 23 are closed by removable hand hole covers 30 and the lower branches 31 of the lower manifold 24 are similarly closed. From each end of the main 25 return pipes 32 and 33 lead back to the corresponding end of the tank C. From the center of the tank C a main 34 leads downwardly to the casing 35 of the oil forcing apparatus from which the oil is distributed by branch pipes 36 and 37 to the opposite ends of the main 38 of the lower manifold.

70 The upper manifold supports the weight of the lower manifold and the heating pipes and is itself supported by I-beams 59' and 60' forming part of the reinforcing structure of the furnace. The tubes 22 are thus free to expand to the full extent necessary by reason of the great variation in temperature to which the pipes are subjected. The tank C is supported by stirrups 57 from 75 scaffolding 58.

80 The upper manifold supports the weight of the lower manifold and the heating pipes and is itself supported by I-beams 59' and 60' forming part of the reinforcing structure of the furnace. The tubes 22 are thus free to expand to the full extent necessary by reason of the great variation in temperature to which the pipes are subjected. The tank C is supported by stirrups 57 from 85 scaffolding 58.

85 The upper manifold supports the weight of the lower manifold and the heating pipes and is itself supported by I-beams 59' and 60' forming part of the reinforcing structure of the furnace. The tubes 22 are thus free to expand to the full extent necessary by reason of the great variation in temperature to which the pipes are subjected. The tank C is supported by stirrups 57 from 90 scaffolding 58.

95 The oil forcing apparatus illustrated comprises a spiral or screw propellor arranged in a barrel 40, the shaft 41 of the propellor being provided at its outer end with a driving pulley 42 or other means for transmitting power thereto. By rotating the propellor in the proper direction, the oil in the still is forced to circulate rapidly from the pump upwardly through the heating tubes 100 to the tank and thence back to the pump. A stuffing box 43 is provided about the shaft 41 and is in turn enclosed in a housing 44 which is likewise provided with a stuffing box 45 about the shaft. A pump 46, diagrammatically illustrated in Fig. 1, connected to a supply tank containing oil of the character being treated is provided for forcing oil into the housing 44 through pipe 47 under a pressure somewhat in excess of 105 that within the pump casing 35. A connection 48 having a valve 48^a therein is provided for introducing oil from the housing 44 into the pump casing 35 where it mingles 110 with the oil being treated. A connection 48^b having a valve 48^b therein leads back to the supply tank to which the pump 46 is connected. This tank should be so constructed and should contain a sufficient supply of oil so that the return of oil thereto 115 from the housing 44 does not materially heat it.

120 In carrying out the process of the present invention in circulatory pressure stills of the character illustrated, circulation is main- 125

tained by the pump B and the escape of hot oil at the cracking temperature is prevented by circulating relatively cold oil through the housing about the stuffing box 5 on the pump operating shaft under a pressure in excess of that prevailing in the still so that if any leakage past this stuffing box occurs it is of cold oil into the pump casing and not of hot oil out of the pump casing. 10 Sufficient circulation of cold oil through the housing is maintained to prevent its becoming heated to a dangerous temperature so that it is immaterial if there is leakage past the stuffing box 45 on the housing, although 15 by maintaining this stuffing box and that part of the shaft passing through it at a relatively low temperature, it is much easier to maintain a tight joint at this point. This circulation also cools and protects all of the 20 pump parts external of the pump casing proper and also cools the inner stuffing box 43 so that a tighter joint can be maintained at this point.

Fresh oil may be supplied to the still in 25 this manner and circulated through the housing about the stuffing box on the pump casing on its way to the still. All of the oil to maintain the liquid level in the still may be supplied in this manner, or if the 30 amount of oil required to maintain the still charge is insufficient to provide the desired cooling of the housing, additional oil may be circulated through the housing and thence back to the supply tank through connection 35 48^a. The valves 48^b and 48^c are employed to control the amount of oil recirculated to the supply tank through connection 48^a and introduced into the cracking system through connection 48, respectively.

40 It will thus be seen that the present invention provides an improved method of operation of circulatory pressure stills in which circulation is effected by means of a mechanical forcing means, such as a pump, 45 whereby leakage of hot oil is avoided and the mechanical elements of the forcing means are cooled and protected in an improved manner. In another aspect, it will be apparent that this invention provides a 50 novel and advantageous method of introducing fresh oil into circulatory cracking stills whereby the relatively cold fresh oil is utilized to prevent leakage and to cool and protect the mechanical circulatory means.

55 This application is a division of my prior application filed November 4, 1918, Serial Number 261,109.

I claim:

1. A method of cracking oil in circulatory 60 pressure stills, which comprises mechanically circulating the oil from and to a bulk supply tank through a heater, heating the oil to a cracking temperature in the heater, introducing fresh oil into the circulating oil 65 during the progress of the distillation and

employing the fresh oil for cooling the mechanical circulating means before introducing it into the still.

2. A method of operating circulatory pressure cracking stills in which oil is circulated from and to a bulk supply tank through a heater in which it is heated to the cracking temperature, which comprises mechanically circulating the oil by means operated by an extension extending through a 70 stuffing box and a housing arranged externally of the stuffing box, circulating relatively cold oil through the housing under a pressure in excess of that prevailing in the still and introducing oil from the housing into 75 the circulating oil in the still.

3. A method of operating circulatory pressure cracking stills in which oil is circulated from and to a bulk supply tank through a heater in which it is heated to 80 the cracking temperature, which comprises mechanically circulating the oil by means operated by an extension extending through a stuffing box and a housing arranged externally of the stuffing box, circulating relatively cold oil through the housing under a pressure in excess of that prevailing in the still, and forcing oil from the housing through the stuffing box into the circulating 85 oil in the still.

4. A method of operating circulatory pressure cracking stills in which oil is circulated from and to a bulk supply tank through a heater in which it is heated to the cracking temperature, which comprises mechanically circulating the oil by means operated by an extension extending through a stuffing box and a housing arranged externally of the stuffing box, circulating relatively cold oil through the housing under a 90 pressure in excess of that prevailing in the still and introducing part of the oil circulated through the housing into the oil in the still.

5. A method of cracking oil in circulatory pressure stills, which comprises mechanically circulating the oil from and to a bulk supply tank through a heater, heating the oil to a cracking temperature in the heater, employing fresh oil for cooling the mechanical 100 circulating means and introducing part of the fresh oil employed for cooling into the circulating oil in the still.

6. A method of cracking oil in circulatory pressure stills, which comprises mechanically circulating the oil from and to a bulk supply tank through a heater, heating the oil to a cracking temperature in the heater, introducing fresh oil into the mechanical circulating means so that it first contacts with the hot oil in the still therein and employing the fresh oil for cooling the mechanical circulating means before introducing it into the still.

7. A method of cracking oil in circulatory 110

pressure stills, which comprises circulating the oil from and to a bulk supply tank through a heater, heating the oil to a cracking temperature in the heater, mechanically 5 circulating the oil by means operated by an extension extending through a stuffing box and a housing arranged externally of the

stuffing box, circulating fresh oil through the housing under a pressure in excess of that prevailing in the still and introducing 10 fresh oil from the housing into the circulating hot oil in the still.

In testimony whereof I affix my signature.
EDWARD W. ISOM.
